UNITED STATES PATENT OFFICE.

ELIJAH RASEY, OF LOS ANGELES, CALIFORNIA.

SAFETY ATTACHMENT FOR ELEVATORS.

Application filed March 23, 1921. Serial No. 454,728.

To all whom it may concern:

Be it known that I, ELIJAH RASEY, a citizen of the United States, residing at Los Angeles, in the county of Los Angeles and State of California, have invented a new and useful Safety Attachment for Elevators, of which the following is a specification.

This invention relates to elevators, being more particularly a safety device or attachment for elevators by means of which an elevator, so equipped, is automatically stopped in the event the hoisting cable breaks or releases the car.

The invention resides in mechanism so arranged that arms or dogs mounted on the car engage the racks at the side of the elevator shaft, such dogs being so arranged that a cushioning effect is produced thereby eliminating jar to the car and passengers.

The principal object of my invention is to produce an attachment of the class described of simple form and construction.

Other objects and advantages will appear hereinafter from the following description and drawings.

Referring to the drawings which are for illustrative purpose only.

Fig. 1 is a face view of an elevator, partly in section, equipped with my safety attachment.

Fig. 2 is an inverted sectional plan view on line 2—2, Fig. 1.

Fig. 3 is a sectional view on line 3—3, Fig. 1, and

Fig. 4 is a vertical sectional view on line 4—4, Fig. 1.

In the drawings, 11 indicates the racks on each side of the elevator shaft, such racks being mounted in the usual manner to the shaft timbers (not shown).

The car 12 is suspended on the lifting cable 13, the operation of the car being controlled by any suitable mechanism, not shown as such mechanism forms no part of my invention.

14 indicates the floor of the car supported on cross beams 15 to which are attached two standards 16 on each side of the car. Extending across the top of the car is the cross head 17 consisting of two channel bars 18, such bars being connected to the standards 16 in any suitable manner.

A dog or arm 20 is provided at each side

of the car arranged to engage the respective racks 11, such dogs being slidably mounted in guides 21 formed of plates 22 bolted to the sides of the channel bars 18 and extending under such bars to form supporting guides for the dogs. Each dog is engaged on its upper face by a plate 23 yieldingly mounted on bolts 24 which are supported on the lower flanges of the bars 18. Mounted on each bolt 24 is a compression spring 25 which yieldingly holds the plate 23 against its associated dog.

Vertically slidable in ways 27 between the bars 18 is a plunger 28 connected in any suitable manner to the cable 13. The lower end of the plunger 28 is provided with a head 29 which engages under the bars 18 and supports the weight of the car and load thereby. Each dog 20 is connected to the upper end of the plunger by means of a link 30 so arranged that during the normal operation of the elevator the dogs are retracted or out of the path of racks at the side of the elevator shaft.

In the event the cable 13 should break or slip and fail to support the car, the weight of the plunger 28 causes the plunger to drop and through the medium of the links 30 the dogs 20 are moved into the path of the rack and engage the teeth thereon. This engagement of the rack by the dogs causes the elevator to stop as the elevator is then supported on the dogs 20. As the dogs engage the teeth of the racks, the springs 25 absorb the shock or jar as the weight of the car compresses the springs which yieldingly hold the plate 23 in engagement with the dogs 20.

An auxiliary safety attachment which may be operated by a passenger is mounted in the side of the car and consists of a pivoted arm 35 mounted in a slot 36 in one of the standards 16, such arm being provided at its upper ends with a knob 37 which may be grasped by the passenger. By pulling the knob downwardly, the arm is swung outwardly into engagement with the rack 11, the lower end of the arm coming into engagement with the upper end of a slot 39 in the opposite standard 16. This engagement of the arm with rack causes the car to stop, the weight of the car being supported on such arm.

To insure that the plunger

28 acts promptly to throw out the dogs 20, the plunger may be provided with weights indicated at 40.

I claim as my invention:

- 5 In combination with an elevator shaft including a vertical rack on the side thereof; an elevator car including a pair of standards between which said rack extends; a weighted dog pivoted in one of said standards; and a

handle on said dog for swinging the same 10 across said rack into a slot in the other standard and against the upper end of said slot for arresting the descent of said elevator.

In testimony whereof, I have hereunto set my hand at Los Angeles, California, this 15 18th day of March, 1921.

ELIJAH RASEY.
